UNITED STATES PATENT OFFICE.

LOUIS DIESTERWEG, OF CHICAGO, ILLINOIS.

DESIGN FOR A BOX-LID CLASP.

SPECIFICATION forming part of Design No. 30,947, dated June 6, 1899.

Application filed December 17, 1898. Serial No. 699,601. Term of patent 7 years.

To all whom it may concern:

Be it known that I, LOUIS DIESTERWEG, a citizen of the United States of America, and a resident of Chicago, county of Cook, and 5 State of Illinois, have invented and produced a new and original Design for Box-Lid Clasps, of which the following is a specification, reference being had to the accompanying drawings, forming part thereof.

10 Figure 1 is an end elevation of the clasp from the side which engages the box-lid. Fig. 2 is a back view of the clasp from the side which corresponds to the top side of the lid when the lid of the box is closed.

15 The clasp is made of a flat sheet of metal stamped out in proper form and bent to shape, as indicated in the drawings.

A designates the main plate or display portion of the clasp.

B designates the section which engages the 20 back wall of the box by means of the slot B'.

C designates the lip or flange which engages the lid on the top side or back side when the lid is open.

This peculiarly-shaped design is adapted 25 to be inserted upon a cigar-box or other similar box in a position to lock the cover of the box open and furnish a display for price or name upon the body portion A of the design.

I claim—

The design for a box-lid clasp substantially 30 as herein shown and described.

Signed by me, at Chicago, Illinois, this 29th day of October, 1898.

LOUIS DIESTERWEG.
